UNITED STATES PATENT OFFICE

LESTER L. LEWIS, OF NEW CASTLE, PENNSYLVANIA, ASSIGNOR OF TWO-THIRDS TO
BLAIR STRIP STEEL COMPANY, OF NEW CASTLE, PENNSYLVANIA, A CORPORATION
OF PENNSYLVANIA

ANNEALING APPARATUS

Application filed February 4, 1930. Serial No. 425,812.

This invention relates to improvements in apparatus for heat treating metal for increasing its ductility while largely eliminating discoloration, and has as its essential object the improvement of apparatus such as set forth in detail in my co-pending patent application Serial No. 411,179, filed December 2, 1929.

Reference is had to that application for details of problems and difficulties met and overcome by the present invention which accomplish all of the advantageous results set forth in the said application with the additional advantages of increased efficiency in safeguarding against air leakage and increased facility of uniformity of distribution of the protecting gas.

The invention comprises certain novel constructions, combinations, and arrangements of parts especially well adapted for annealing metal work while precluding access of air to the work being treated, all as will herein-after be set forth and subsequently pointed out in the appended claims.

In the accompanying drawings:—

Figure 1 is a transverse, vertical section through a work receptacle or housing incorporating an embodiment of the invention.

Figure 2 is a horizontal section taken on the plane indicated by line 2—2 of Figure 1 and looking downward, the work being omitted.

Figures 3 and 4 are sections similar to Figure 1 of slightly modified embodiments.

Figure 5 is an enlarged, detailed, fragmentary, sectional perspective of one of the flanges of the tray of Figures 1 and 2.

Figure 6 is a similar fragmentary sectional perspective of a part of one of the side walls of the "pot" or housing which in operation is mounted on the tray.

Figures 7 and 8 are views, respectively, similar to Figures 5 and 6 of slightly modified embodiments of the parts shown.

Figures 9 and 10 are views similar, respectively, to Figures 7 and 8 of further slight modifications.

Any well known and standard type of annealing furnace will, of course, be employed after the manner indicated in my above-identified, co-pending application. It is com-

mon practice to place metal work to be annealed in an appropriate housing, seal the housing, and then insert the housing in a furnace where the work is raised to the requisite temperature for the required length of time for accomplishing the annealing operation, after which the housing and its contents of work are withdrawn and allowed to cool.

A popular form of housing consists of a tray provided with grooves in its under face to guide the tray on a track of rollers which leads into the furnace, and upon the tray is commonly mounted an inverted, trough-like receptacle customarily referred to as a "pot". The tray is provided with upstanding flanges, and the pot is proportioned to rest on the upper surface of the tray within the flanges spaced sufficiently therefrom to accommodate sealing material for sealing the joint between the pot and tray. Various forms of comminuted matter have been used to effect the sealing operation. Sand has been successfully used by me.

Referring to the drawings by numerals, 1 indicates the tray having the track-receiving grooves 2, 2 and the upstanding and surrounding marginal flange 3. During operation, the casing or pot 4 is mounted on the tray 1 and is dimensioned to allow an appropriate space between the lower part of the side walls of the pot and the surrounding flange 3 to provide a sealing space in which is placed the sand or other comminuted sealing material 5. The lower edge of the casing or pot 4 may rest directly on the upper surface of the tray 1, but, as a further means of sealing, a portion of the comminuted material is preferably disposed beneath such edge so as to be caused to become compact by the weight of the pot and thus resist movement of air past the line of jointure between the pot and the tray. Work of any appropriate character, such as indicated at 6, is arranged on the tray 1 within the pot 4.

As made clear in my above-identified co-pending application, I have discovered and proved by successful tests that the attempts heretofore made to protect the work 6 by the seal and by supplemental means, such as the direct introduction of gas into the pot 4,

have not fully accomplished the ends in view and have not safe-guarded the work against discoloration; whereas I have succeeded in effectively preventing discoloration of the 5 work by distribution of gas not within the pot 4 but within the sealing sand 5, and, as set forth in my said co-pending application, I have been especially successful when distributing the gas by a tube or gas supply pipe 10 embedded in the sand 5 approximately midway between the pot 4 and the adjacent flange of the tray, the pipe being provided with appropriate jets for the discharging of gas and the gas being supplied under pressure 15 sufficient for causing the gas to envelop the entire area about the pot 4 within the flange 3. The pressure of gas employed is sufficiently above atmospheric pressure to effect sealing against ingress of air despite formation of 20 25 30 vacuum within the pot 4. In the practicing of the invention according to the specific embodiment set forth in my said co-pending application, however, it is necessary to apply and remove the gas supplying coil or tube 25 with each successive operation, and the present invention avoids the necessity for such labor and the inconvenience of handling the parts under the surrounding conditions.

To this end, a gas supplying passageway 30 is formed in one of the parts adjacent the seal 5 in position to jet gas into the seal entirely about the same so as to effectively take the place of the removable coil or pipe disclosed in my said co-pending application, 35 and for purposes of this application a structure may be considered as preferred by me when providing such a passageway at both sides of the seal 5, though I have successfully accomplished very desirable results 40 with such passageway at one side only. In the carrying out of a physical embodiment of the invention, the flange 3 is provided with a gas passageway or port 7 entirely about the flange with which communicates a gas 45 supply pipe 8, the passageway or port 7 being provided with appropriate vents discharging into the sand seal 5. Also, in the preferred embodiment a port or passageway 9 is formed in the wall of the pot 4 entirely about the pot 50 and is supplied with gas through a pipe 10 having a flexible hose connection 11 detachably connected to the pipe 10. The port 9 is vented into the space occupied by the seal 5, so that gas may be jetted from both sides of 55 the sealing sand 5 into the same to maintain a sufficiently high resistance to prevent ingress of air. The details of the mode of formation of the passages or ports 7 and 9 are susceptible of almost innumerable variations, and it will be understood that all such variations are within the intent, purpose, and scope of the present invention. One effective embodiment is illustrated in Figure 1 of the drawings and consists of the provision of an inwardly-opening rabbet about the upper

margin of the flange 3, which rabbet is substantially closed by an angle bar 12 welded at 13 along that edge contacting with the uppermost portion of the flange 3. The pendent or lower flange of the angle bar 12 has 70 its lower edge spaced sufficiently from the base of the rabbet to provide an appropriate jetting opening 14 for the gas. The size of the opening 14, as shown in the drawings, is exaggerated for purposes of disclosure, but, 75 in fact, the opening is so narrow as to hardly be discernible in a drawing of the proportions employed. It will be obvious, of course, that the total cross sectional area of the entire passageway 14 about the entire flange 3 80 should be slightly less or certainly not more than the total cross sectional area of the gas supply pipe 8, so as to insure effective jetting of the gas into the sealing material 5. The port 9 similarly is provided by forming a 85 groove in the outer face of the vertical wall of pot 4, which groove extends entirely about the pot, and an angle bar 15 is arranged with its horizontal flange extending into said groove and welded along a line 16 to the pot 4. 90 The lower or pendent flange of the angle bar 15 is spaced from the lower wall of the said groove similarly to the spacing of the pendent flange of angle bar 12 from the base of the rabbet of flange 3, whereby an appropriate 95 jetting opening 17 corresponding in location and dimensions to the opening 14 is provided so as to jet the gas supplied through pipes 10 and 11 into the sealing material 5 from the opposite side from the gas jetted from the 100 passageway 7.

As clearly shown in Figures 7 and 8, the jetting openings 14 and 17 may assume the form of perforations 14' and 17', respectively, or any other form adapted for effective distribution of gas across the area between the flange 3 and the pot 4. As the structural parts seen in Figures 7 and 8 are otherwise identical with those seen in Figures 1, 5, and 6, the same description will equally apply and the same reference numerals have, therefore, been applied to said Figures 7 and 8.

As seen in Figures 9 and 10, the jetting openings may be provided by having the 115 pendent flange of the angle plate overlap the adjacent surface of the wall of the pot or flange, as the case may be, to produce a downwardly instead of laterally directed opening, as seen, respectively, at 14" in Figure 9 120 and at 17" in Figure 10. The structural parts shown in Figures 9 and 10 aside from this overlapped condition with the resulting directional change in the jet being identical with that above described, the same description 125 will equally apply and the same reference numerals have been employed on said Figures 9 and 10.

The operation is the same as that described in my above-identified co-pending application 130

except for the delivery of the gas at the sides of the sealing space instead of substantially midway thereof. The coils, strips, bars, or other work 6 are placed on the tray 1 and the pot 4 lowered down over such work. The sand or other appropriate comminuted sealing material 5 is then tamped in the space about the pot 4 within the flange 3. Ordinarily, a small portion of sand will have been placed in position to receive the lower edges of the pot 4 as they come to rest on the tray 1 so as to enhance the sealing effect. The sealing material is preferably tamped in place until the entire space is filled, and then the housing or enclosure for the work consisting of the tray and pot is moved into the annealing furnace. It should be understood, of course, that the flexible pipe 11 is detached and a sufficient portion of the connections for the pipe 8 is also detached to allow the structure to move freely into the furnace. After the required baking, the work and its enclosure are withdrawn and allowed to cool. Just as soon as the parts are removed from the furnace, the connections for pipes 8 and 10 are made and gas is supplied under pressure and the supply is maintained until the cooling operation has been completed. I have not yet been able to prove just what operation occurs, but I know definitely that unusual and spendid results occurred. My hypothesis is that the gas delivered to the sealing material 5 creates an upward pressure and though the gas ignites and burns that fact does not destroy the upward pressure and such upward pressure counterbalances atmospheric pressure and prevents any air from finding its way into the pot 4 under the edges thereof. Also, since the gas burns freely little if any finds its way into the pot, or at all events, whatever gas does find its way into the pot does no injury since through numerous successful tests I have been able to produce steel work having a highly polished surface absolutely free from spots or stains or other discolorations such as occur when air finds it way into the pot 4, or as occur under whatever conditions arise when a counterbalancing pressure of gas is introduced directly into the pot 4 rather than into the sealing space.

I also find that it is entirely feasible to produce highly satisfactory results by the employment of a single gas-discharging passageway. For instance, the passageway 7 may be employed without the employment of the passageway 9, or the passageway 9 may be employed without the employment of the passageway 7, and if the gas under pressure is continuously supplied during the cooling operation, the finished work is found to be free from discoloration.

In Figure 3, I have illustrated the structure provided with the single passageway in the flange of the tray, while in Figure 4 I have illustrated the same combination with

the passageway provided in the pot alone, and as these structures are otherwise identical with those shown in Figures 1, 2, 5, and 6, the same reference numerals have been applied to these figures of the drawings and the same descriptive matter is applicable.

It will be of course, understood that the jet openings 14', 17', 14", and 17" will all be of sufficiently reduced cross sectional area to allow substantially uniform distribution of gas from the supply pipe and, accordingly, the total cross sectional area of the jets in any instance will not exceed the cross sectional area of the gas supply pipe. And it should also be understood that while the gas passageways have been thus illustrated and described as produced by a substantially integral formation of the material of the walls of the enclosure, other modes of providing the gas passageways may well be employed, such as the welding of an appropriate tubing in proper location with respect to the parts.

The art or process disclosed herein is not made the subject of claim in this application because it is claimed in my co-pending application Serial No. 479,051, filed August 30, 1930.

What is claimed is:—

1. In apparatus for heat treating metal work, an enclosure for work having a sealing space and having a gas passage in the wall of the enclosure extending along and discharging into said space throughout the length of the space.
2. In apparatus for heat treating metal work, an enclosure for work having a sealing space and having a gas passage in the wall of the enclosure extending along and discharging into said space throughout the length of the space, in combination with means for supplying gas under pressure to said passage.
3. In apparatus for heat treating metal work, an enclosure for work having a sealing space and having a gas passage in the wall of the enclosure at each side of said space extending along and discharging into said space throughout the length of the space.
4. In apparatus for heat treating metal work, the combination of separable enclosure parts spaced to provide a sealing opening between said parts, one of the parts being formed with a gas passageway extending along and communicating with said opening substantially continuously throughout the length of the opening.
5. In apparatus for heat treating metal work, the combination of separable enclosure parts spaced to provide a sealing opening between said parts, each of the parts being formed with a gas passageway extending along and communicating with said opening substantially continuously throughout the length of the opening.
6. In apparatus for heat treating metal

- work, the combination of separable enclosure parts spaced to provide a sealing opening between said parts, one of said parts being formed with a cutaway portion, and a cover plate for said cutaway portion enclosing a space to provide a gas passageway and means for supplying gas under pressure to said passageway, the passageway venting into the sealing-opening space.
7. In annealing apparatus, a tray adapted to receive work and to receive an enclosing housing for the work, the tray being formed with a gas passageway in outer portions of its walls having discharging outlet means extending substantially continuously throughout the margin of the tray for discharging gas inward from and along said margin.
8. In annealing apparatus, a tray adapted to receive work and to receive an enclosing housing for the work, the tray being formed with a gas passageway in outer portions of its walls discharging inward from and along the margin of the tray substantially continuously of said margin, and means for supplying gas under pressure to said passageway.
9. In apparatus for annealing metal work, the combination of a tray for receiving metal work to be annealed, an enclosing housing adapted to surround metal work on the tray, the tray and housing being formed with gas passageways in their walls, and means for delivering gas under pressure to said passageways, the passageway for the tray having discharge openings toward the housing and the passageway of the housing having discharge openings toward the tray.
10. In annealing apparatus for metal work, the combination of a tray and a pot adapted to be removably mounted on said tray, the tray being provided with an enclosing flange surrounding and spaced from the pot to provide a sealing space therebetween, and means providing gas passageways about the pot and about the flange of the tray, each of said passageways having means of discharge into said sealing space.
11. In annealing apparatus for metal work, the combination of a tray and a pot adapted to be removably mounted on said tray, the tray being provided with an enclosing flange surrounding and spaced from the pot to provide a sealing space therebetween, and means providing a gas passageway in the wall of and about the pot, said passageway having means of discharge into said sealing space.
12. In annealing apparatus for metal work, the combination of a tray and a pot removably mounted on the tray, the tray being provided with an enclosing flange surrounding and spaced from the pot to afford a sealing space therebetween, and means providing a gas passageway within and about the wall of one of said parts, the passageway having means of discharge into the sealing space.
13. In annealing apparatus for metal work, the combination of a tray and a pot adapted to be removably mounted on said tray, the tray being provided with an enclosing flange surrounding and spaced from the pot to afford a sealing space therebetween, and means providing a gas passageway in the wall of and about the flange of the tray, said passageway having means of discharge into said sealing space.
- In testimony whereof I affix my signature.
